US0D1017506S

(12) **United States Design Patent** (10) **Patent No.:** **US D1,017,506 S**
(45) **Date of Patent:** **** Mar. 12, 2024**

(54) **BOAT**

(71) Applicant: **DECATHLON**, Villeneuve d'Ascq (FR)

(72) Inventor: **Valentin Pena Martin**, Villeneuve d'Ascq (FR)

(73) Assignee: **DECATHLON**, Villeneuve d'Ascq (FR)

(**) Term: **15 Years**

(21) Appl. No.: **29/811,730**

(22) Filed: **Oct. 15, 2021**

(30) **Foreign Application Priority Data**

Apr. 21, 2021 (EM) 008511687-0001

(51) **LOC (14) Cl.** **12-06**

(52) **U.S. Cl.**

USPC **D12/316**

(58) **Field of Classification Search**
